UNITED STATES PATENT OFFICE.

WILLIAM R. BETHAM, OF CHICAGO, ILLINOIS.

CAR-COUPING.

SPECIFICATION forming part of Letters Patent No. 474,806, dated May 17, 1892.

Application filed February 3, 1890. Serial No. 338,995. (No model.)

To all whom it may concern:

Be it known that I, WILLIAM R. BETHAM, a citizen of the United States, residing at Chicago, county of Cook, State of Illinois, have 5 invented a new and useful Improvement in Car-Couplers, of which the following is a specification.

The object of my invention is to provide a simple and durable car-coupler which will 10 couple up automatically when the cars come together and avoid the necessity of having the brakeman go between them.

It consists of two hooked draw-bars swinging on horizontal axes, which hook onto one 15 another as the ends of the cars strike together and the buffer-springs are compressed.

It further consists of details of construction and operation hereinafter more fully described, and particularly pointed out in the 20 claims.

Figure 1 is a side elevation of the ends of two cars coupled together with my coupler, part of the timber of one car being broken away to show the buffer-socket. Fig. 2 is a 25 plan view of one of the couplers looking down, the car-body being removed. Fig. 3 is a detail of the socket into which the tail-piece of the draw-bar fits. Fig. 4 is a sectional view of Fig. 1. Fig. 5 is a sectional view showing 30 the draw-bar raised, as in uncoupling. Figs. 6, 7, and 8 are detail views of the draw-bar.

A represents the timbers of the cars; B, the buffers set in the ends of the timbers; C, the draw-bars; D, the socket into which the tail-piece C' of the draw-bar fits. The socket D is attached to the draw-bolt L and draws against the draw-spring J. It is provided with studs O O on each side, which slide in the guides M M. The draw-bar is tilted by 35 means of the lever F, attached to the shaft E. This shaft E also has attached to it two arms G G, which come upon each side of the draw-bar, and an arm H extending out from the shaft below it. These arms are attached to 40 the draw-bar by the chains I I and I'. When the cars are to be uncoupled, the lever F is swung backward and the arms G G, through the chains I I, pull up on the draw-bar on one side of a shifting-fulcrum, and the arm H, 45 through the chain I', pulls down upon it upon the other side, the tail-piece C' sliding freely in the curved socket D. In this manner the

draw-bar is tilted up, as shown in Fig. 5, until it is uncoupled from its fellow draw-bar.

The socket D is curved, in order to allow 55 the tail-piece to swing in it, and made sufficiently long to prevent the tail-piece from coming out of engagement when the draw-bar is tilted. The tilting of the draw-bar is limited by the car-body above and the cross-tie S 60 below.

The slack in the chains allows of the necessary longitudinal movement of the draw-bar.

The hooks or flanges T T, which form the head of the draw-bar, are made the one with 65 its inner face concave, as shown in Fig. 6, and the other with its inner face convex, as shown in Figs. 4 and 5, so that when one draw-bar couples with his fellow draw-bar on the other car the convex flange on the one fits 70 into concave flange on the other. The object of this shaped flange is to provide for turning curves, so that the one will slip over the other more readily and still retain a firm hold.

The head of the draw-bar is tapered off, so 75 that one will mount upon the other when they come together. The taper is made long enough to enter the socket of the ordinary link-and-pin coupling in common use, and a hole P is cut in it to receive the pin, thus adapting my 80 coupling to be used with the link-and-pin coupling.

The buffers B B project sufficiently that in order to couple the cars they must be compressed, as shown in Fig. 4, and their expansion pressure then tends to keep the cars apart and the draw-bars hooked together. 85

What I claim, and desire to secure by Letters Patent, is—

1. The herein-described car-coupler, consisting of the combination of the hooked draw-bar, the draw-spring, and the socket attached thereto, into which the tail-piece of the draw-bar fits, all substantially as shown and described. 90

2. The herein-described car-coupler, consisting of the combination of the hooked draw-bar, the draw-spring, the socket attached to said spring, into which the tail-piece of the draw-bar fits, and the lever by means of which 100 said draw-bar is raised or lowered, all substantially as shown and described.

3. The herein-described car-coupler, consisting of the combination of the hooked draw-

bar, the draw-spring, the socket attached to said spring, into which the tail-piece of said draw-bar fits, the lever by means of which said draw-bar is raised or lowered, and the buffers, all substantially as shown and described.

4. The herein-described car-coupler, consisting of the combination of the draw-bar C, having the flanges T T and the tail-piece C',

the curved socket D, the draw-spring J, attached thereto, the shaft E, having the lever F, and the arms G G, and the arm H, attached thereto, and the chains I I, and the chain I', all substantially as shown and described.

WILLIAM R. BETHAM.
